UNITED STATES PATENT OFFICE

113,963

DESIGN FOR A CHECKER BOARD

Charles Henry Brown, Breckenridge, Tex.

Application December 20, 1938, Serial No. 81,903

Term of patent 7 years

To all whom it may concern:

Be it known that I, Charles Henry Brown, a citizen of the United States and a resident of Breckenridge, in the county of Stephens and State of Texas, have invented a new, original, and ornamental Design for a Checker Board, of which the following is a specification.

Reference is had to the accompanying drawing forming part thereof, in which:

Fig. 1 is a plan view of a checker board showing my design,

Fig. 2 is an edge view of the checker board.

I claim:

The ornamental design for a checker board, as shown.

CHARLES HENRY BROWN.
